CHARLES H. NIXON, OF DETROIT, MICHIGAN.

ADJUSTABLE HINGE.

1,265,363.

Specification of Letters Patent.

Patented May 7, 1918.

Application filed March 23, 1917. Serial No. 156,874.

To all whom it may concern:

Be it known that I, CHARLES H. NIXON, a citizen of the United States, residing at Detroit, in the county of Wayne and State 5 of Michigan, have invented a new and useful Adjustable Hinge, of which the following is a specification.

This invention relates to hinges especially adapted for use in mounting swinging doors 10 of buildings.

The invention has for its object the provision of a hinge of simple and comparatively inexpensive construction which may be readily applied in the usual way, but with 15 greater facility in effecting the proper hanging of doors, in which provision is made for pivotally connecting the leaves of the hinge in a manner to render them bodily removable relatively so as to enable adjustments to 20 be made to compensate for variations in the door or casing and insure an even fitting and free swinging of the door.

In attaining the above object the invention contemplates, briefly described, the employment of a pair of hinge leaves each having pintle knuckles and which are joined in adjacent parallel relation by interconnecting links interposed between the pintle knuckles. The ends of the links engaged 25 with the stationary leaf of the hinge freely embrace the pintle thereof and form the pivotal bearings upon which the companion leaf of the hinge swings, while the ends of the links engaged with the swinging leaf 30 tightly embrace the pintle thereof under sufficient frictional stress to normally prevent pivotal movement of the engaged parts, yet yielding under the application of undue stress to permit of the shifting of the pintle 35 about the pivotal axis of the stationary hinge to vary the distance between the leaves without altering their parallel relation or 40 disturbing their fixed positions upon the stationary and swinging members.

45 A preferred structural embodiment of the essential features of the present invention is illustrated in the accompanying drawings, in which,

Figure 1 is a perspective view of a hinge 50 constructed in accordance with my invention.

Fig. 2 is a horizontal sectional view through a portion of a door and casing, showing the hinge in end elevation attached 55 thereto and indicating by dotted lines an adjusted position of the hinge leaves.

Fig. 3 is a fragmentary detail in perspec-

tive of portions of the hinge members disengaged.

Fig. 4 is a vertical sectional view through 60 the hinge knuckles and connecting links on dotted line 4-4 of Fig. 2.

Referring to the parts by the characters of reference marked on the drawings, 1 represents the frame or jamb of a doorway 65 within which the door 2 is hinged to swing, 3 indicates a stop for the door and 4 the casing for the door frame, all of which is common.

The body of the hinge consists of two 70 plates or leaves 5 and 6 preferably stamped to form of sheet metal and provided with holes 7 for the reception of screws 8 by which said leaves are attached respectively to the jamb and door being seated in mortises formed therein in the usual way. See 75 Fig. 2. The stationary or jamb leaf 5 is provided at its outer edge with a series of spaced axially alined pintle knuckles 9 which are offset to overlie the plane of the inner 80 face of the leaf by an arcuate extension 10, and the outer edge of the swinging or door leaf 6 is provided with a series of correspondingly spaced pintle knuckles 11 which normally nest within the arcuate extension 85 of the leaf 5 and lie in adjacent transverse alinement parallel with the knuckles 9 thereof.

Inserted in the registering spaces between the knuckles of the hinge leaves to extend 90 transversely thereof is a connecting link or links 12, each comprising two parallelly connected knuckles which lie in axial alinement with corresponding barrels of the leaves and receive the respective hinge pintles 13 and 95 14 which are extended through said knuckles, as shown in Figs. 1 and 4. The pintle 13, which extends freely through the knuckles of the stationary leaf and the connecting links, forms the pivotal axis on which the 100 links turn together with the swinging leaf and door carried thereby, and the body of this pintle, which is preferably removable, is divided near one end and provided with a cap or plug 15 fixed in a knuckle of the 105 hinge in the usual way. The pintle 14 connecting said links with the door leaf is made to fit sufficiently tight in the knuckles of said members to resist by frictional contact pivotal movement of the joint under the normal 110 stress exerted thereon by the resistance of the links in turning upon the pintle of the fixed leaf through the swinging movement of the door, but permitting of relative move-

ment.

ment of the members forming this joint when subjected to added stress under the application of leverage force or impact to break the joint and change the angular relation of the links and door leaf so as to effect an adjustment bodily of the leaves of the hinge.

Under ordinary conditions the frictional contact afforded by a tight fit of the pintle 14 within the knuckles of the links and door leaf is sufficient to retain them in set relation against accidental displacement, but in certain uses of the hinge, as when carrying unusually heavy doors, it may be desirable to 15 fixedly secure one or more of the links to the pintle 14 in order to more positively bring into service the frictional surfaces of the knuckles of the door leaf which collectively embrace the pintle over a greater bearing 20 surface than that afforded by the knuckles of the links, and thus resistance to the turning of the connected members of the joint will be increased. This may be effectively accomplished by inserting a pin 25 transversely through the knuckle of the link and pintle as indicated at 16. See Fig. 4.

Where smaller hinges for lighter work are required the hinge leaves may be formed with a single pair of spaced knuckles for the 30 reception of a single connecting link in which the pintle of the swinging leaf may be tightly fitted therein and in the knuckles of the leaf, or it may be fixedly secured in the link knuckle by means of a pin as may 35 be desirable to regulate the frictional resistance of the joint.

From the foregoing description of the construction the operation of the hinge should now be understood as follows: It 40 will be noted that the door leaf and connecting link normally swing together upon the pintle of the stationary leaf, and as the angular position of the connecting link to the plane of the door leaf determines the nested 45 or spaced relation of the two leaves it will be apparent that by exerting sufficient force upon the link to turn it to the desired angle upon the pintle of the door leaf the space between the leaves may be varied to shift 50 the door transversely and effect an adjustment thereof to secure the proper fitting or clearance with the jamb or casing. This may be readily accomplished without disengaging the hinge or necessitating the disengagement or adjustment of any of the parts 55 thereof further than to drive or force the knuckle of the link into or out of the arcuate extension of the jamb leaf to effect an adjustment correspondingly of the door leaf 60 and door.

I claim:

1. A hinge comprising two leaves, and a

link pivotally connected to each of said leaves, said link having fixed engagement with the pivotal connection of one leaf and 65 restrained against movement relative thereto by frictional engagement of the pivotal connection with said leaf.

2. A hinge having two leaves each provided with a pair of spaced pintle knuckles, 70 a link interposed between the knuckles and connecting said leaves, a pintle forming a pivotal connection between said link and the knuckles of one leaf, and a pintle tightly embraced by said link and the knuckles of 75 the other of said leaves and frictionally restraining said members against pivotal movement.

3. A hinge having two leaves each provided with a pair of correspondingly spaced 80 pintle knuckles, the knuckles of one leaf being offset to overlie the plane of the face of said leaf by an arcuate extension embracing the knuckles of the companion leaf, a connecting link having knuckles interposed respectively between the knuckles of said leaves, and pintles pivotally connecting the knuckles of said link with the respective knuckles of said leaves, one of said pintles being restrained against pivotal movement 90 by frictional engagement with the embracing knuckles.

4. A hinge having two leaves each provided with a pair of spaced pintle knuckles, one of said leaves having an offset arcuate extension for the reception of the knuckles of the companion leaf, a connecting link having knuckles interposed respectively between the knuckles of said leaves, pintles pivotally connecting the knuckles of said link with the respective knuckles of said leaves, one of said pintles being restrained against pivotal movement by frictional engagement with the knuckles of the connected leaf, and means to fixedly secure said pintle to the 105 engaged knuckle of said link.

5. A hinge having two leaves each provided with a pintle knuckle, one of which knuckles is offset to overlie the plane of the face of its leaf by an angular extension 110 adapted to embrace the knuckle of the companion leaf, a link connecting said leaves having knuckles respectively registering with the knuckles thereof, and pintles pivotally connecting the knuckles of said link with the respective knuckles of said leaves, one of said pintles being restrained against pivotal movement by frictional engagement with one of the embracing knuckles, and means to fixedly secure said pintle to the 115 other embracing knuckle.

In testimony whereof I sign this specification.

CHARLES H. NIXON.
